[57] CLAIM

The ornamental design for a combined motorcycle engine guard and highway footrest, as shown and described.

DESCRIPTION

FIG. 1 is a front perspective view of the combined motorcycle engine guard and highway footrest showing my new design;

FIG. 2 is a front elevational view thereof, the rear elevational view being a mirror image thereof;

FIG. 3 is a top plan view thereof;

FIG. 4 is a bottom plan view thereof; and,

FIG. 5 is a right side elevational view, the left side elevational view being a mirror image thereof.

Fig. 1
